UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,227,801.

Specification of Letters Patent. Patented May 29, 1917.

Application filed October 2, 1911. Serial No. 652,424.

To all whom it may concern:

Be it known that I, CHARLES J. KLEIN, a citizen of the United States, residing at Milwaukee, in the county of Milwaukee and 5 State of Wisconsin, have invented new and useful Improvements in Electric-Switch Devices, of which the following is a full, clear, concise, and exact description, reference being had to the accompanying drawing, 10 forming a part of this specification.

My invention relates to electric switch devices.

It has among its objects to provide an improved electric switch device which is 15 adapted to make or break a circuit with a quick snap action. It has further among its objects to provide an improved electric switch mechanism of unit form which may be readily inserted or removed when desired from a suitable inclosing casing. Other objects and advantages of my improved construction will hereinafter appear.

In the accompanying drawings I have 25 illustrated three forms which my invention may assume in practice. My invention is not however, limited to these forms chosen for purposes of illustration, but may assume other forms.

30 In the views of these drawings:—

Figure 1 shows a side elevation of the switch mechanism in position in a casing.

Fig. 2 shows a central sectional view on line 2—2 of Fig. 1.

35 Fig. 3 shows perspective views of the operating members raised in elevation one over the other.

Fig. 4 shows a perspective view of a modified form of switch mechanism with a portion of the operating parts withdrawn.

Fig. 5 shows a similar view of a further modified form of switch mechanism.

In the construction shown in Figs. 1 and 2 I have illustrated a snap switch mechanism of the push button type carried upon an insulating base provided with suitable terminal connections which permit the same to be inserted in a suitable insulating casing or socket having two parts 1 and 2 in 45 substantially the same manner as described in my copending application, Serial No. 651,224, filed Sept. 25, 1911.

The switch mechanism proper is carried upon an insulating base 3 preferably of a 50 disk shape which is seated in a suitable re-

cess or chamber 4 in one of the parts of the socket or casing so that the switch mechanism lies in a plane substantially parallel with the inner surface of the casing. An operating member 5 is provided at its opposite ends with push buttons 6 which are arranged to reciprocate through suitable openings 7 on the opposite sides of the casing. This operating member is provided with a longitudinally disposed slot 8 between its ends and is arranged to be reciprocated across the base 3. In a preferred form suitable projections 9 forming a substantially rectangular shaped slot 10 between the same are provided upon one side of the 60 operating member preferably near one end of the slot 8. A central shaft 11 is preferably suitably journaled in the base 3 and extends vertically upward through the slot in the operating member. This shaft is preferably 65 inclosed where it passes through the operating member in a sleeve 12, preferably of rectangular cross section, arranged to fit within the slot 8 and provided with a central vertically extending bore 13 arranged 70 to receive the shaft 11. As the shaft 11 is fixed to the base 1 the amount of movement of the operating member across the base is limited by the engagement of the sides of the member 12 with the ends of the slot 8. 75 Coöoperating with the operating member 5 and arranged to be actuated by the same, is a cam member 14 which is preferably located below the operating member and arranged to be rotated about the shaft 11 by 80 the engagement of the projections 9 with a projection or stud 15 which extends upward from the body of the cam member 14. The lower surface of the cam member 14 is preferably serrated as shown at 16 in Figs. 2 90 and 3 in order to provide a series of cam surfaces which preferably extend entirely around the bottom surface of the cam member 14. As illustrated in Fig. 2 the member 12 preferably rests upon the upper surface of this cam member and is held in position against the same by means of a spiral spring 17 which encircles the upper end of the shaft 11. In a preferred form this 95 spring is housed in a suitable recess in a second insulating base 18, arranged to fit over the switch mechanism and which if desired may be held to the base 3 by any suitable means. The serrated cam surfaces of the cam member 14 are arranged to en- 100 105 110

gage bearing surfaces 19 on a movable contact member 20 pivoted upon the central shaft 11 beneath the cam member. In a preferred form I form the bearing surfaces 19 of steel balls seated in suitable recesses in the movable contact member 20 on opposite sides of the perforation through which the shaft 11 extends, and beneath the serrated cam surface of the cam member 14. 5 However, instead of using steel balls I may obviously use other forms of bearing surfaces as for instance struck-up portions from the body of the movable contact member. The contact surfaces of the contact member 20 are located at its ends and are 10 preferably beveled as shown at 21 in Fig. 3. These contact surfaces are arranged to engage suitable stationary contacts 22 mounted on opposite sides of the base 3. It is of course obvious that if desired a plurality 15 of these contact members may be used and the device thus adapted to control a plurality of circuits. In a preferred form the contact surfaces 22 are provided with extended portions 23 of the type described in 20 my previously mentioned co-pending application, and the base 3 is provided with suitable extensions which permit it to be inserted or removed from the casing 1 and 2 by simply adjusting a suitable screw or 25 other fastening means 24. As in that application the member 1 of the base may be provided with a suitable terminal strip 25 adapted to be connected to a threaded 30 ducting shell 26 carried in the bottom of the casing, and the center contact of the device may be formed by the extension 27 on the lower stationary contact 22. The two parts 1 and 2 of the casing may also be suitably 35 secured together by means of a screw 28 in a manner similar to that described in 40 that application.

When it is desired to operate a switch mechanism of the type shown in Figs. 1 to 45 3 inclusive, all that it is necessary to do is to push in one of the push buttons 6. The operating member 5 then moves across the base 3 carrying with it the projection 15 on the cam member 14, to rotate this cam member 50 and compress the spiral spring 17. When the crest of a pair of the cam surfaces 16 on the cam member 14 pass over the bearing surfaces on the movable contact member 20 the tension upon the spring 17 is released 55 and the bearing surfaces pass down the opposite inclines of the cam surfaces, throwing the movable contact member 20 about its pivot with a quick snap action which tends to break the circuit at the stationary contacts 22 with but little sparking so that the contact surfaces are able to withstand long use in service. By the provision 60 of the wiping engagement of the contact surfaces 21 with the extensions 23 of the stationary contacts 22, the contact surfaces

are kept clean so that there is very little loss through poor contacts.

In Fig. 4 I have illustrated a modified form which my invention may assume. In this figure I have illustrated a switch mechanism carried upon an insulating base 29 similar to the base 5, and arranged to be reciprocated across the same in substantially the same manner. In this instance the operating member 30 is provided with a slot 31 arranged at one side of the same and near its center, the movement of the operating member being limited by the engagement of the ends of the slots with the central shaft 32. In this construction the operating member 30 is beneath the movable contact member rather than above the same as shown in the previous construction and this operating member carries upon its surface preferably at a point adjacent the slot 31, and at one side of the same, the bearing surfaces 33 which coöperate with the cam member. The cam member 34 in this construction is preferably attached to the under side of the movable contact member 35 and is preferably provided with a cam surface similar to that just described. In this construction the movable contact member is spring-pressed by a spiral spring 36, one end of which presses down upon the upper surface of the movable contact member, while the other end abuts against an adjustable tap 37 carried on the threaded end of the shaft or spindle 32. When the operating member 30 is reciprocated across the base 29, the bearing surface is moved in this construction to force the cam member and the movable contact member upward to compress the spring. When the bearing surface is moved out from under one of the crests of the cam 34 the tension of the spring is released and the movable contact member is oscillated about the shaft 32 with a quick snap action to make or break contact at suitable stationary contacts 38 which may be constructed similar to the contacts 32 heretofore described. In order to limit the movement of the movable contact member, suitable stops 39 may be provided on opposite sides of the base 28.

In Fig. 5 I have illustrated a further modified form which my invention may assume in practice. In this construction the operating member 40 is provided with any suitable handle 41 and is arranged to oscillate to cause the movable contact member 42 to oscillate, and a plurality of bearing surfaces 43 are provided on the upper surface of the movable contact member 42. As in the previous construction these bearing surfaces may if desired assume the form of steel balls, and as in the construction shown in Fig. 4 the cam member may be attached to the operating member. In this construction the movement of the operating member

115

120

125

130

carries the cam surfaces over the bearing surfaces and compresses the spring, which when the bearing surfaces have moved over the cam surfaces is released to throw the 5 movable contact member to circuit making or breaking position with a quick snap action.

By the use of my improved construction I have provided a snap switch mechanism 10 which is adapted to make or break a circuit with a quick snap action. Further the construction is one which may be made of a small number of parts which may be readily manufactured and is one which is adapted 15 to withstand long use in service. Further, by the improved arrangement and construction of parts, the switch mechanism may be made very compact so that it occupies but little space and which is of such a type that 20 it may be readily adapted to a wide range of uses.

While I have in this application described several specific forms which my invention may assume in practice, I do not 25 wish to be limited to these specific forms, but wish rather to include within the scope of this application all of those forms of my invention which fall within its spirit.

What I claim as new and desire to secure 30 by Letters Patent of the United States is:

1. In an electric switch, in combination, two movable members, one a contact member and the other an actuating member, said members being relatively movable in 35 parallel planes, a rigid projection on one of said members, a rigid cam on the other of said members, and resilient means holding said projection and said cam in constant yielding engagement.
2. In an electric switch, in combination, a rotatable contact member, a movable actuating member therefor, said members being oppositely movable in parallel planes and having rigid engaging parts, and resilient means holding said parts in constant 45 yielding engagement.
3. In an electric switch, in combination, a rotatable contact member, a reciprocable operating member therefor, an operative 50 connection between said members comprising a rotatable peaked cam movable with one and a projection movable with the

other, and resilient means holding said cam and said projection in constant yielding engagement.

55

4. In an electric switch, in combination, an oscillating contact actuating member, a reciprocating operating member therefor, and an operative connection between the same for imparting a snap movement to the former 60 upon reciprocation of the latter comprising an oscillating peaked cam connected to one of said members, and one or more rigid projections on the other member having rounded surfaces to engage said cam, and means resiliently holding said cam and said projection or projections in engagement.

65

5. In an electric switch, in combination, an oscillating contact, rigid projections thereon having rounded surfaces, a second oscillating member having a peaked cam surface, a spring holding said oscillating cam in engagement with said projection on said contact member, and a reciprocating member connected to said cam to oscillate the same.

70

6. In an electric switch, an insulating base, a spindle projecting therefrom, a reciprocable operating member having a longitudinally disposed slot and a transversely disposed slot, said operating member being arranged to reciprocate across said base and having said spindle extending through one of said slots, a cam member rotatably mounted upon said spindle, said cam member having a serrated active surface and an upwardly extending projection, means for limiting the movement of said operating member and for positioning said cam member, and an oscillating movable contact member having bearing surfaces arranged to engage the active surface of said cam member, said contact member being arranged to be oscillated about said spindle with a quick snap action in an opposite direction to the direction of movement of said cam member after 90 said cam member has traveled through approximately half of its travel.

85

In witness whereof, I have hereunto subscribed my name in the presence of two witnesses.

CHARLES J. KLEIN.
